UNITED STATES PATENT OFFICE

JACOB GOODMAN, OF BROOKLYN, NEW YORK

HAIR WAVER

Application filed August 11, 1930. Serial No. 474,515.

This invention relates to improvements in hair wavers, more especially to those of the type described in an application, Serial No. 416,311, filed by myself and another, on December 26, 1929.

It is the object of this invention to devise a waving device of the type described in the above-entitled application, wherein a further result will be obtained in the form 10 of a lateral wave in addition to the usual vertical wave effect. In general, this main object of the invention is attained by the arrangement substantially of a pair of independent wave crest forming members 15 secured relatively to each other, the securing means acting also as a mounting for the sliding of a comb, which in turn supplies the lateral wave effect.

It is a further object of this invention to 20 devise a wave forming device of the above described type which may be constructed of cheap material and by cheap manufacturing methods, since articles of this type must be sold at a very low price. Further objects of this invention will be apparent from 25 a review of the specification and drawings.

Referring now to the drawings where a preferred form and a modification of my invention is shown:

30 Figure 1 is a plan view of the device showing the type of lateral wave formed thereby.

Fig. 2 is a side view thereof.

Fig. 3 is a section along the line 3—3 of 35 Fig. 1.

Fig. 4 is a section along the line 4—4 of Fig. 1.

Fig. 5 is a section along the line 5—5 of 40 Fig. 3.

Fig. 6 is a perspective view of a modification of my invention.

Referring now more particularly to the drawings, reference numeral 10 indicates a wire-like element bent to form a loop having 45 parallel sides 11 and 12, and a constricted or crimped portion 13. Each of the parallel portions 11 and 12 terminate respectively in ends 14 and 15 which are coiled about a flanged sleeve or rivet 16. The member 16 50 carries a spacer sleeve 16' so formed as to

hold loops 10 in spaced relation on the member 16 as will be readily understood.

There are two of these loop members 10, and in cooperation with these members, I have a U-shaped loop 17 having parallel 55 portions 18 and 19. These parallel portions terminate in ends 20 and 21, each of which is coiled about the shaft 16 between the coiled ends 14 and 15 of the loops 10. This construction allows for relative pivotal 60 movement between the U-shaped loop 17 and the loop members 10.

The crimped portion 13 and the rivet or sleeve 16 are raised with respect to the parallel portions 11 and 12 of the loops 10 as 65 is apparent from the drawing. The U-shaped loop 17 is adapted to enter the constricted or crimped portions 13 to form a resilient lock for maintaining its arms 18 and 19 in the position of Fig. 1. Because 70 of the raised relation of the pivot or sleeve 16 and the crimped locking portions 13, the parallel U sides 18 and 19 of the U-member 17 will occupy a raised position relatively to the portions 10 and 11. This will confine 75 the hair as shown in Fig. 1 and will form a pair of wave crests along the line of each of the parallel members 18 and 19.

Mounted on the pivot 16 is a comb mounting member 22 which may be of any particular type for mounting a comb 23 relatively to said pivot. This mounting member is equipped, preferably, with a pair of rivets 24 and the comb is cut out at 25 so that it may slide on said rivets relatively to the 80 mounting member and the waving device in general.

Joining the loop members 10 and 11 at a point substantially removed from the pivot 16, although not necessarily at the extreme 85 point illustrated in Figure 1, is a narrow plate member 26 which holds the loop members 10 in fixed relation relatively to one another. This member 26 is shaped as shown in detail in Figure 4 and rides in a slot 27 in the comb 23 whereby the comb will 90 slide in definite relation to each of the loops 10.

I will now describe the operation of my 95 device and its results.

It will be readily understood that the hair waver when applied to the hair, forms a pair of wave crests by means of each of the loops 10 and the U-member 17 which has the parallel leg portions 18 and 19 traversing the longitudinal center of each of these loops 10. The trough of the wave will be formed at the bases of the teeth of the comb 23 which are located in a plane substantially below that of the crest forming members 18 and 19. A sliding movement of the comb 23, as is quite apparent, will then move the hair comprising the trough of the wave in a lateral direction relatively to the crests thereof, which are being held in a fixed position, while this lateral motion takes place. This will give the professional waving effect clearly illustrated in Figure 1 comprising a pair of wave crests 20 and a trough, the hair of the trough being laterally as well as vertically displaced from the hair of the crests.

Referring now more particularly to Figure 6, I illustrate a modification of my invention wherein the loop members are unsecured as in the position of Figure 1, by a member 26. This allows for a free pivotal movement of each of the loops 10 and 11 relatively to the pivot shaft 16 and the spacer sleeve 16'. The comb mounting member 22 is pivoted on this shaft 16 and carries slidably secured thereto the usual comb 23 as is described in the first modification. This comb carries a handle portion 35 28 by which it may be actuated in a sliding direction. This handle 28 has a further function in that it acts to interlock with the loop member 17 to hold the comb in an extended position as is quite clear in Figure 6. Whereas I do not show this handle 28 in the modification of Figures 1 to 5 inclusive, it should be understood that the same may be used therein in the same relation as in Figure 6.

From the above description, the operation and construction of my device should be clear. Although I have described but two embodiments of my invention, it will be understood that modifications of the same 50 within the scope of the appended claims will readily occur to one skilled in the art.

What I claim is:

1. An article of the class described comprising a pair of U-shaped members, central members traversing each of said U-members, each of said U-members and its respective traversing member acting to form and position the crest of a hair wave, and a central comb mounted between said U-members and adapted to shift the position of the hair of the trough portion of said wave relatively to said crests.

2. An article of the class described comprising a pair of U-shaped members, central members adapted to traverse each of

said U-members and to be secured relatively thereto to form a pair of wave crests, a comb arranged between said pair of members and slidably relatively thereto, the plane of said comb being in the trough of the wave formed by said crests, whereby to shift the hair of said trough laterally relatively to the crests. 70

3. An article of the class described comprising a pair of independent loops having parallel sides and formed of wire-like material, an end shaft, the ends of said loops being secured on said shaft in spaced relation, traversing wires mounted on said shaft and arranged to traverse the longitudinal center of each of said independent loops, and a comb slidably mounted relatively to said end shaft for movement between said pair of loops. 75

4. An article of the class described comprising a pair of independent loops having parallel sides and formed of wire-like material, an end shaft, the ends of said loops being secured on said shaft in spaced relation, traversing wires mounted on said shaft 90 and arranged to traverse the longitudinal center of each of said independent loops, and a comb mounting carried on said shaft between said pair of loops. 80

5. In the combination of claim 4, a comb carried by said mounting and movable relatively thereto. 95

6. In the combination of claim 4, a comb carried by said mounting and slidably relatively thereto, means securing said independent loops at points substantially removed from said end shaft, said means forming a bearing for the sliding of said comb. 100

7. An article of the class described comprising a pair of independent loops formed of wire-like material, an end shaft, the ends of said loops being secured on said shaft in spaced relation to each other, a single U-shaped wire pivotally mounted on said shaft, the sides of said U-wire being arranged to traverse the longitudinal center of each of said independent loops, a comb mounting secured to said shaft, and a comb mounted for sliding movement relatively to 110 said mounting. 105

8. In the combination of claim 7, means securing said independent loops to each other at a point substantially removed from said end shaft, said means forming a bearing portion for said sliding comb. 115

9. An article of the class described comprising a pair of independent loops having parallel sides and formed of wire-like material, an end shaft, traversing wires mounted on said shaft and arranged to traverse the longitudinal center of each of said independent loops, and a comb mounted for pivotal and sliding movement relatively to 125 said shaft. 120

10. An article of the class described comprising a pair of independent loops having parallel sides and formed of wire-like material, an end shaft, the ends of said loops being secured on said shaft in spaced relation to each other, a single U-shaped wire pivotally mounted on said shaft, the sides of said U-wire being arranged to traverse the longitudinal center of each of said independent loops, a comb mounted for sliding movement relatively to said shaft, and means for securing said comb relatively to said U-wire.

11. In the combination of claim 10, said securing means being a knob like element fixed to said comb to facilitate manual operation thereof.

Signed at New York in the county of New York and State of New York this 8th day of August A. D. 1930.

JACOB GOODMAN.
